UNITED STATES PATENT OFFICE.

WILLIAM S. HAMM, OF CHICAGO, ILLINOIS.

SIGNAL-LAMP.

SPECIFICATION forming part of Letters Patent No. 651,782, dated June 12, 1900.

Application filed May 16, 1898. Serial No. 680,815. (No model.)

To all whom it may concern:

Be it known that J. WILLIAM S. HAMM, of Chicago, in the county of Cook and State of Illinois, have invented certain new and useful Improvements in Signal-Lamps, of which the following is a specification, reference being had to the accompanying drawings and to the numerals of reference marked thereon.

This invention relates more particularly to improvements in signal-lamps such as are employed in connection with railway-switches, although it is obviously applicable to different classes of lamps, as tail and other descriptions used in railway practice, and to lamps or lanterns for a variety of purposes.

The lamp or lantern to which my invention is more especially intended to be applied is commonly used in the open air and exposed to various temperatures, and it has been found that what is known as "sweating" is produced by unequal temperatures on opposite sides of the lenses. This sweating is caused by moisture held in suspension by the warm air within the lamp or lantern condensing on the inner faces of the lenses when the lamp is exposed to a temperature lower than that within the lamp. Such lamps or lanterns, particularly in railroad practice, are subjected to extreme cold, as from 10° to 40° below zero; but such excessive cold is not required to produce the injurious effect named, as it is found to exist even where the temperature is at or near the freezing-point.

One of the objects of my invention, therefore, is to prevent sweating, and thus preserve an unobscured and brilliant light.

A further object of my invention is to prevent the downward rush of air either under the top cap or through the openings provided to admit fresh air for combustion, tending to extinguish the flame. It is obvious that an unprotected lamp or lantern or one exposed to the action of the elements is liable to great variations of atmospheric temperature and that unless means are adopted for preventing or deflecting the downward rush of air into the lamp, whether received under the cap or at the air-openings, the flame must be extinguished. To overcome this injurious effect is another object of my invention.

A further object is to prevent the choking up of the hot-air outlet by the heavier cold

air or otherwise, which also has the tendency to extinguish or smother the flame or render it less brilliant. This injurious action, while constantly observed by railroad hands and trainmen, has been ascribed to various conditions. It may be mentioned that such action occurs not only when the lamp is stationary, but when carried about or where it is used with switches, gates, or other moving objects. To prevent this result is another object of my improvement.

In the fuller description of the invention which follows reference is had to the drawings, in which—

Figure 1 represents a side elevation, partly in section, of a switch-lamp embodying my invention. Fig. 2 is a horizontal section on line 2 2. Figs. 3 and 4 are detail views of detached parts.

Similar numerals of reference indicate similar parts in the respective figures.

1 is the main body of the lamp, having radial lens-openings, of which there may be two, three, or four, according to the use or service to which the lamp is applied. The lamp-body is preferably made of Bessemer steel and of the general character set forth in my Patent No. 549,314, granted November 5, 1895. In my said former patent is shown a cone (marked 10) arranged within the upper portion or section 2 of the lantern-casing, and which extends from a point at or near the top of the lens-openings to the upper region of the said section. The cone is connected to the said upper portion of section 2 of the casing by means of an annular plate or diaphragm. The part 2 of the casing above the plate or diaphragm is cylindrical, there being necessarily a wider space around the upper portion of the cone than at its base, and a series of openings 9 are provided in the said part 2 of the casing at or near the bottom of the cone.

In my present invention a cone similar to that of my Patent No. 549,314 is employed, but the upper portion or section of the outer casing is differently shaped and the openings therein are differently placed. In my present invention the upper portion of section 2 of the casing is hinged to the plate 3, as shown, the hinging-point 4 being substantially in the plane of the annular plate or diaphragm of

Patent No. 549,314. Therefore the top of the cone 10 in my present invention extends some distance above the hinging-point, and the hinged portion 2 of the casing instead of being cylindrical, as is the stationary corresponding portion of Patent No. 549,314, is made conical, so that its sides are substantially parallel to the outer surface of the cone 10. The top of the hinged cone 2 is contracted and is practically of the same diameter as that of the upper end of the cone 10. Above the top of the hinged cone 2 and arranged a short distance above it is the cap 5, secured to the hinged cone 2 by standards 6. The cap 5 is of a diameter considerably greater than that of the top of the hinged cone 2 and effectually protects the interior of the lamp from the beating in of rain due to high winds and the like. It is not essential to my invention 20 that the cone 2 be hinged. Openings 7 are made through the upper part of the casing 1, just below the hinged cone 2, through which openings air enters to support combustion. Within the upper part of the casing 1 is an 25 upright cylinder 8 of perforated metal, open at each end, its upper end being secured to the casing 1 just below the openings 7. The perforated cylinder 8 extends downwardly into the casing a greater or lesser distance, as 30 required for the perfect operation of the lamp. The lower end of the cylinder 8 is for a short distance left imperforate. The space bounded by the plate 3, cylinder 8, and cone 10 forms an air-chamber, within which currents 35 of fresh air entering through the openings 7 are effectually quieted before passing into the body of the lantern through the perforated cylinder 8. The cone 10 is provided at its base with an upwardly-turned flange 9, so 40 formed as to leave a space between the base of the cone and the outer portion of the flange 9, which outer portion is secured to the perforated cylinder 8 by means of a bayonet-joint or other easily-detached connection. 45 It has been found that in the use of a lamp or lantern of the construction herein described the several defects heretofore noticed are avoided. The sweating of the lenses is prevented by the increased volume of cold 50 air which enters the lantern through the perforations in the cylinder 8, thus insuring (as nearly as possible) an even temperature on the inner and outer surfaces of the lamp-body and the lenses, which can only be 55 cured by keeping a sufficient volume of cold air the temperature of which is substantially that of the outer air between the inner surface of the lamp-body and the central current of hot air from the burner. The fresh air 60 entering the openings 7 immediately below the plate 3 strikes the outside of the cone 10 and is deflected by it upwardly against the under side of the plate 3, which in turn deflects it downwardly to the base of the cone, 65 where it is again turned upwardly and passes thence through the perforated cylinder 8 into the lantern. The various changes of the di-

rections of the currents of air tend to still or quiet them.

The lower end of the cylinder 8 being imperforate, the entering air cannot pass directly into the lamp when deflected downwardly by the plate 3. To obtain the necessary quantity of cold air within the lantern, it has been found necessary to carry the base 75 of the cone 10 into the lantern. This, however, is not objectionable, as it is apparent that within certain limits the nearer the base of the cone 10 is to the flame the more quickly will the hot air pass through the cone and 80 out of the lamp under the cap 1. This rapid movement of the hot air will carry the whole of it out of the lamp, leaving none to mingle with the incoming cold air, and at the same time it will effectually prevent the cold air 85 from passing down through the cone into the lamp, which would extinguish the flame or cause it to flicker and reduce the power of the light.

The absence of films upon the inner faces of 90 the lenses is obviously a positive advantage in a signal lamp or lantern, inasmuch as any obscuration of light may be attended with disastrous results.

I do not confine myself to the exact construction herein described, as deviations may be made therefrom by the skilled mechanic without the exercise of invention. Neither do I insist upon the entire accuracy of the statement of principles under which the 95 proved advantages herein stated to attend this construction are found. It is believed, however, that the novel operations and results described are the direct result of my invention as set forth.

It is obvious that the air-chamber need not be annular in horizontal or transverse section, but that it may be of other shape, provided it is a walled structure.

Having thus described my invention, I 110 claim—

1. The combination, with a lantern, of an annular air-chamber depending thereinto remotely situated with reference to the burner and communicating with the combustion-chamber thereof, the said annular chamber comprising an inner imperforate and an outer perforated air-distributing wall, and being closed at its lower end and provided with air-inlet openings communicating with the external air, and the central passage of the annular air-chamber constituting an escape-flue for the products of combustion, substantially as set forth.

2. The combination, in a lamp or lantern, 125 of a casing or body having a series of openings for the admission of air, a perforated cylinder within the casing or body and secured thereto below the openings, and a cone attached to the perforated cylinder and passing through it and the top of the casing or body, substantially as set forth.

3. The combination, in a lamp or lantern, 130 of a casing or body having a series of open-

ings for the admission of air, a perforated cylinder within the casing or body and secured thereto below the openings, a cone passing through the perforated cylinder and the top of the casing, and an outer cone above the casing and provided with a cap, substantially as set forth.

4. The combination, in a lamp or lantern, of a casing or body having a series of openings near its top for the admission of air, a perforated cylinder within the casing or body and secured thereto below the openings, and a cone passing through the perforated cylinder and detachably secured to its lower end, substantially as set forth.

5. The combination, in a lamp or lantern, of a casing or body, a plate in the upper part of said casing or body, an internal cone extending above and below the said plate, a perforated cylinder connected to the base of the said internal cone, an outer cone above said plate, surrounding the internal cone and

extending above the same, said outer cone being open at the top, and a cap above said outer cone, the casing or body being provided, 25 immediately below said plate, with openings, substantially as set forth.

6. The combination, in a lamp or lantern, of a casing or body, and an air-chamber in its upper part consisting of the plate 3, cylinder 8 and cone 10, said chamber extending into the casing or body and having a series of openings for the admission of air from without, and perforations for the exit of air into the casing or body, said air-chamber constituting means for deflecting and quieting the currents of air before they pass into the lantern, substantially as set forth.

In testimony whereof I hereunto set my hand and seal this 2d day of May, 1898.

WILLIAM S. HAMM. [L. S.]
